DOOR HINGE

Roy E. Bartimore, Milwaukee, Wis., assignor to
Roy E. Bartimore, as trustee

Application October 13, 1933, Serial No. 693,468

5 Claims. (Cl. 16—136)

The invention relates to hinges for automobile doors or other swingable members and more particularly to hinges of the concealed type.

An object of the invention is to provide a strong and durable hinge capable of economical manufacture and having a rolling support to secure easy action and to reduce wear, there being arcuate grooves for rollable members so arranged as to facilitate machining operations and entry of the rollable members.

Another object of the invention is to provide a hinge having resilient means for retaining a rollable bearing member in engagement with a race-way.

15 A further object of the invention is to provide a hinge having a pair of bearing members spaced axially thereof and so arranged as to resist relative tilting of the hinge members incident to looseness at the pintle.

20 The invention further consists in the several features hereinafter described and claimed.

In the accompanying drawing,

Fig. 1 is an elevation of a door hinge embodying the invention as it appears when secured to a co-operating door and door frame, the latter parts being shown in section;

Fig. 2 is a sectional view taken along the line 2—2 of Fig. 1;

Fig. 3 is a sectional view taken along the line 3—3 of Fig. 1, the door being swung open;

Fig. 4 is a sectional view taken along the line 4—4 of Fig. 1;

Fig. 5 is a detail sectional view of a resiliently mounted ball bearing;

Fig. 6 is a view, partly in section, of a modified form of hinge;

Fig. 7 is a sectional view taken along the line 7—7 of Fig. 6;

Fig. 8 is a sectional view similar to Fig. 3 showing another modified form of hinge, the hinge being in closed position, and

Fig. 9 is a sectional developed view taken along the line 9—9 of Fig. 8.

In the drawing, 15 designates the door post or jamb of an automobile body, and 16 a door occupying a doorway 17 in the body. The door post 15 is covered at its outer and inner sides by respective panels 18 and 19, respectively, and the door 16 is similarly faced with outer and inner panels 20 and 21, respectively. The outer door panel 20 has a weather flange 22 which overlies the edge of the body panel 18 when the door is closed, as seen in Fig. 2.

The door is supported by two or more hinges embodying the invention, one being shown. In

that form of the invention shown in Figs. 1 to 5, the door post has a cavity 23 formed therein to receive a stationary hinge member or casing 24, which is provided with upper and lower flanges 25 let into the door post and secured thereto by screws 26. At least one of the flanges 25 may be extended, as indicated, to constitute a part of a similar hinge member of another hinge, not shown, to thus facilitate alignment and to strengthen and form part of the door post. 10

The hinge member 24 has spaced parallel cheeks 27 connected at portions distant from the flanges 25 by a wall 28 and forming therewith a recess 29 which opens at the doorway. A forwardly projecting hinge knuckle 30 is carried on 15 the wall 28 midway between the cheeks. The wall 28 is here shown to include an angular portion 31 at the side nearest the inner body panel 19.

A movable hinge member 32 has a hooked portion 33 fitting between the cheeks 27 of the stationary hinge member, the hinge member 32 having opposite parallel faces 34 adjacent these cheeks. The hooked portion has a pair of spaced hinge knuckles 35 which fit between the knuckle 25 30 and the cheeks 27 and are secured thereto by a pintle 36 fast to the stationary hinge member, the pintle being arranged near one side edge of the stationary hinge member and between the open front and the rear wall of the latter hinge 30 member. The movable hinge member has a flange 37 which is let into the door and secured thereto by screws 38. The flange 37 may be extended, if desired, to form part of another similar hinge member, in the same manner as the flange 35 on the stationary hinge member.

When the door is closed, the hinged edge thereof lies adjacent the edge of the door post 15, and the weather flange 22 lies close to the body panel 18. The extreme opening movement of the door 40 is limited, as seen in Fig. 3, by the engagement of a recessed portion of the movable hinge member with a stop pin 39 connecting the cheeks 27 and disposed between the pintle and the front opening of the stationary hinge member. The 45 stop pin 39 and pintle 36 are fastened to the cheeks in any suitable manner, as by a drive fit. In the open position of the door, the hinge member 32 extends only a small distance into the doorway and has no projection on which clothing 50 may catch. The open door does not appreciably reduce the effective width of the doorway.

The inner faces of the cheeks 27 are provided with arcuate grooves or tracks 40 concentric with the axis of the pintle 36. Both ends of the tracks 55

open at the outer side edges of the cheeks so that they may be formed, preferably at the same time, by a cutter rotating continuously in one direction. The upper and lower faces of the hooked portion of the movable hinge member are provided with arcuate grooves or tracks 41 and 42, respectively, registering with the grooves 40. Rollable members 43 and 44, preferably balls, are mounted in the upper and lower grooves to roll therealong when the door is swung, and are entered into the cheek grooves 40, during assembly, at the open ends of these grooves. The lower ball 44 resists both axial and radial thrust on the hinge. The upper ball rolls on an arcuate trackway plate 45 mounted in the groove 41 and pressed upwardly by resilient means such as a corrugated metal spring strip 46 below the plate, so as to urge the ball 43 upwardly against the upper cheek groove 40, thereby compensating for wear and variations in manufacture. The upper ball resists radial thrust on the hinge. The upper and lower balls are here indicated to be in alignment on a line parallel to the pintle axis, and are kept in such position by their abutment with the ends of the grooves 41 and 42 when the door is swung to its extreme positions. The ends of the cheek grooves 40 are concealed by the body panel 18.

As the door is swung, the movable hinge member is supported to a large extent on the rolling ball 44. Movement of the hinge member in a radial direction is resisted by both balls 43 and 44, thus relieving the pintle of most of the radial load. Each arcuate ball track has a relatively large radius without requiring an excessively wide and deep hinge, and a single ball in the track provides an effective anti-friction bearing.

In the modified form of hinge shown in Figs. 6 and 7, the stationary hinge member is made in upper and lower halves 124 and 124' secured in abutment by a shouldered pintle 136 and shouldered stop pin 139 riveted to the upper and lower cheeks, and by a shouldered pin 147 arranged at the rear wall of the hinge member and riveted to the cheeks. The intermediate hinge knuckle is omitted, but in some instances may be used. The movable hinge member 132 is similar to the hinge member 32 except for the portion surrounding the pintle.

In the modified form of hinge shown in Figs. 8 and 9, the stationary hinge member 224 is similar to the hinge member 24 but has an added vertical wall 248 extending between the front flange and the rear wall at the side opposite the pintle. The movable hinge member 232 is similar to the hinge member 32 except for the disposition of the balls and the omission of the resiliently mounted plate for the upper ball track 241 which is similar to the lower track 242. As best seen in Fig. 9, the lower ball 244 is in advance of the upper ball 243, so that any tipping

or twisting tending to lift the rear portion of the movable hinge member will be resisted by the balls. When the door is swung to its extreme positions, the balls engage ends of the grooves 241 and 242, or stop pins 249 in the 5 grooves, to maintain the relative position of the balls.

What I claim as new and desire to secure by Letters Patent is:

1. The combination of a pair of pivotally connected hinge members, one of which has a cheek and the other of which has a portion adjacent said cheek, said cheek having an arcuate groove concentric with the axis of said hinge members and said groove having open ends at an edge of 15 said cheek, a rollable member movable in said groove and movably bearing on the other hinge member, and means for preventing the escape of said rollable member from said groove.

2. The combination of a hinge member having spaced cheeks and a wall connecting said cheeks and forming therewith a recess, said recess having a front opening and a side opening, a second hinge member having a portion between said cheeks and movable through said front opening, means for pivotally connecting said hinge members, at least one of said cheeks having an arcuate groove concentric with the axis of said hinge members, said groove having an open end at said side opening of the recess, a rollable member movable in said groove and movably bearing on the other hinge member, and means for preventing the escape of said rollable member from said groove.

3. The combination of a pair of pivotally connected hinge members one of which has spaced cheeks receiving between them the other hinge member, a pair of rollable members respectively mounted between each cheek and an adjacent face of said second hinge member, and means for 40 confining said rollable members in an arcuate path of travel concentric with the axis of the hinge members, one of said rollable members being in advance of the other to resist relative twisting movement of said hinge members.

4. The combination of a pair of pivotally connected hinge members one of which has an arcuate groove concentric with the axis of the hinge members and having open ends, an arcuate trackway on the other member having limiting stops, 50 and a rollable member movable in said groove and movably bearing on the trackway of the other hinge member and being limited in its travel by said stops.

5. The combination of a pair of pivotally connected hinge members one of which has a cheek provided with an arcuate trackway having both ends open, a rollable member movable along said trackway and movably bearing on the other hinge member, and means for preventing the escape of 60 said rollable member from said trackway.

ROY E. BARTIMORE.
